No. 694,912.

Patented Mar. 4, 1902.

C. J. DORSEY.

PLURAL FUSE CUT-OUT.

(Application filed Aug. 30, 1900. Renewed June 21, 1901.)

(No Model.)

UNITED STATES PATENT OFFICE.

CHARLES J. DORSEY, OF BALTIMORE, MARYLAND, ASSIGNOR OF ONE-HALF
TO JACOB FELSENSTEIN, OF BALTIMORE, MARYLAND.

PLURAL-FUSE CUT-OUT.

SPECIFICATION forming part of Letters Patent No. 694,912, dated March 4, 1902.

Application filed August 30, 1900. Renewed June 21, 1901. Serial No. 65,507. (No model.)

To all whom it may concern:

Be it known that I, CHARLES J. DORSEY, a resident of Baltimore, in the State of Maryland, have invented certain new and useful Improvements in Plural-Fuse Cut-Outs; and I do hereby declare the following to be a full, clear, and exact description of the invention, such as will enable others skilled in the art to which it pertains to make and use the same.

10 The invention relates to plural-fuse cut-outs and cut-out boxes for electric circuits, and has for its objects to insure certainty and efficiency in action, whereby the circuit is broken, and ease and certainty in the renewal 15 of a broken circuit.

The invention consists in the construction herein described and pointed out.

In the accompanying drawings, Figure 1 is a plan of the device opened. Fig. 2 is a central section of the device closed. Fig. 3 is a transverse section.

Numerical 1 denotes a frame of any convenient or desirable form and material to contain metal electric connections and insulating material *x*. Preferably the frame is provided with brackets 2 for securing it to a car or other structure.

3 denotes a frame to hold a cover 4, and 5 denotes hinges connecting the frames. If desired, the frame 3 may have a casing-plate 6.

7 denotes ventilating-apertures in the cover and its casing-plate. The form and number of these openings are not material and may be varied at pleasure or they may be dispensed 35 with without defeating the other parts of the invention.

9 and 10 denote wires of an electric circuit secured, respectively, to metal bars 12 and 11 by binding-screws 13 and 14.

40 15 and 16 denote short fusible conductors connecting the bar 11 with blocks 17, made of conducting material, and 20 is a key having a shank 18 and conducting part 21 for completing the circuit between the block connected with any particular fusible conductor 45 16 and the bar 12. The bar 12 is forced toward the blocks 17 by springs 18' and 18'', and 19 denotes abutments or portions of the non-conducting inclosure that hold the bar a 50 suitable distance from blocks 17. The blocks and bars may be provided with shallow con-

cave seats to receive the key when turned to an operative situation.

20 denotes a key having a non-conducting handle, preferably molded on the metallic or 55 conducting part 21 of the key, which may be made oblong in cross-section, with its shortest diameter a little less than the distance between the bar 12 and the blocks 17. The electrical circuit is completed by inserting 60 the key through one of the openings 22 in the inclosure or cover and turning it so as to bring the longest diameter of the key part 21 transverse to the bar 12. This compresses 65 the springs and insures a good electrical contact.

22^x denotes shoulders on the key, one of which when the key is inserted and turned, as just stated, engages under a bar or flange 23, whereby the key is held in place. 70

The fuses 15 or 16 may be of any suitable form and material.

24 denotes binding-keys to provide for conveniently replacing the fuses melted out.

25 denotes a fork to engage one of a pair of 75 binding screws, and 26 a hook to engage another.

The improvement contemplates fuses in- closed in tubes and other fuses.

Preferably the blocks 17, the fuse-receptacles 27, and the bar 11 will be fixed or formed, as the case may be, in the body of non-conducting material by molding said material in a plastic state and subsequently hardening it. The part of the cover having receptacles 28, 80 85 which coact to inclose the fuses, can also be formed by molding, ventilating-openings of any suitable shape being provided, if desired.

While it is practicable to make the box of two parts molded from a non-conducting material or composition, other forms built up of separate pieces are not excluded. The frames that surround the non-conducting material are convenient and suitable, but not essential in all cases, and the two parts of the box or 90 inclosure may be connected in any practicable manner.

Heretofore the fuse connections made of spring-plate and constituting movable circuit-closers have been liable to be partially melted 100 and have also been welded to the coacting electrodes by the metal blown from a sud-

denly-melted fuse, and particles of the fuse have also been deposited and hardened on adjacent connections, so that when they were subsequently put in circuit such particles prevented thorough completion of the circuit, with the result that they were remelted and welded the parts together. By my construction the use of a spring or sheet-metal circuit closer is obviated and a key is used of sufficient thickness to prevent fusion. Further, this key has a wide bearing on the contiguous parts of the circuit, and connection is maintained by spring-pressure in such a way that its functions cannot be disturbed by particles of a melted fuse. If such particles are lodged on the key, it will not be on its bearing portions, and the rotation of the key against spring-pressure insures a thorough electrical contact when it is moved to complete the circuit through a new fuse.

The ease with which the fuses can be supplied in the box and the ease and certainty with which they can be put in circuit are important advantages. It is also an advantage that the conductors and their connections are fixed in integral blocks of non-conducting material and that such blocks can be made to inclose the fuses and constitute a box therefor. The provision for ventilation permits the ready escape of suddenly-expanded air, vapor, and gases without injury to the electrical connections when a fuse is suddenly melted or "blown." The receptacles for the fuses are such as to permit the use of various kinds without inconvenience. The parts are of such form and arrangement and are so combined that small metal pieces other than the fuses are avoided. This and other objections to the rotary fuse cut-outs heretofore proposed are obviated. It will be understood that any suitable materials can be employed and that the mechanical modifications above mentioned and other like changes may be made, provided the substantial principles of operation and construction are not departed from.

Having thus described my invention, what I claim as new, and desire to secure by Letters Patent, is—

1. In a thermal electrical cut-out, a series of fuses each connected at one end to the main circuit, conductor-blocks connected to the other ends of the fuses, a detachable key whereby any fuse can be put in circuit, and a non-conducting inclosure having holes corresponding to the fuses for inserting the key, and having also ventilating-openings adjacent the fuses.

2. In a thermal electrical cut-out, a series of fuses each connected at one end to the main

circuit, conductor-blocks connected to the other ends of the fuses, a detachable key whereby any fuse can be put in circuit, and a non-conducting inclosure having holes corresponding to the fuses for inserting the key, said key having its conducting part oblong in cross-section and directly removable from the inclosure.

3. In a thermal electrical cut-out, a series of fuses each connected at one end to the main circuit, conductor-blocks connected to the other ends of the fuses, a key whereby any section can be put in circuit, and a non-conducting inclosure having holes corresponding to the fuses for inserting the key, said key having its conducting part oblong in cross-section and means to lock it in position when turned to complete the circuit.

4. In a thermal electrical cut-out, a circuit comprising two separate bars, a series of fusible conducting-sections each connected to one of said bars, a series of conducting blocks or parts connected to the other ends of the said fusible conducting-sections, and a detachable key to connect the block of any section at will with the other bar, the conducting portion of said key being oblong in cross-section.

5. In a thermal electrical cut-out, a circuit comprising two separate bars, one of said bars being movable, a series of fusible conducting-sections each connected to one of said bars, a detachable key to connect any section at will with the other bar, and springs to hold the movable bar in suitable relation to the sections.

6. In a thermal electrical cut-out, two electrodes, a key for use in closing a circuit between the electrodes, said key having its conducting part oblong in cross-section and provided with the shoulder to engage behind a retaining-bar, and means for rotatably supporting it between the electrodes.

7. In a thermal electrical cut-out, hollow receptacles for fuses, a conductor connected to the fuses at one end thereof, means for making contact between the opposite end of each fuse and another conductor, and binding-posts at each end of the receptacles, said receptacles having a non-conducting cover with ventilating-openings adjacent the fuses for escape of metal.

In testimony whereof I have signed this specification in the presence of two subscribing witnesses.

CHARLES J. DORSEY.
